MECHANICAL PENCIL

By H. Davis, Fenwick, Ontario, Canada

Application March 15, 1934, Serial No. 715,687

25 Claims. (Cl. 120—18)

The present invention pertains to a novel automatic or mechanical pencil that has certain objects in common with the pencil shown and described in my earlier application, Serial No. 5 339,507, filed February 13, 1929.

Ordinarily a mechanical pencil embodies feeding mechanism consisting of a tube having a spiral slot and a longitudinally slotted channel tube in concentric relation, a lead carrier within these 10 parts, and an expelling pin within the carrier. Fingers project from the carrier and pin through the slot in the channel tube and into the spiral slot in the other tube. Rotation of one of the tubes imparts a lengthwise motion to the carrier 15 and expelling pin. At the forward end of the movement, the forward end of the expelling pin passes out of the carrier and thereby expels the last fragment of the consumed lead. A mechanical pencil is also usually formed with a chamber 20 or magazine for lead, and in order to obtain access thereto, it is often necessary to detach a part of the pencil assembly. Some inconvenience is experienced in replacing this part while holding the new lead or laying it aside, for the magazine 25 must be closed to avoid spilling the leads while manipulating the pencil in refilling.

To permit insertion of the new lead, it is necessary to operate the pencil manually in the reverse direction to retract the expelling pin into 30 the carrier member. With the lead initially inserted in the carrier, the pencil must be operated to withdraw the lead into the pencil until only the forward point thereof is exposed. The principal objects of this invention are to eliminate 35 the inconveniences of removing a lead in the conventional manner described and of operating the pencil manually in order to insert the new lead.

The first of these objects is accomplished by a 40 novel construction of the magazine whereby a lead is delivered or made accessible by sliding one of the pencil casing sections outwardly relative to the other rather than removing a part entirely from the assembly. An outward pull on 45 the shiftable or relatively movable body section exposes a groove formed in the operating tube on which the section is mounted. This groove is in communication with the magazine and is so positioned that it readily receives a lead from the 50 magazine. Suitable finger dents are provided at the sides of the groove in order to facilitate taking hold of the lead therein.

The second main object is accomplished by 55 constructing the feed mechanism in such a way that it is readily reversible by pressure of the

new lead on the exposed end of the expelling pin, without manual rotation or operation of the feeding mechanism. The conventional feeding mechanism described above requires ordinarily that the two tubes be attached respectively to the 5 relatively rotatable parts of the pencil body. So long as these connections are maintained, the mechanism can be operated in reverse direction only by turning one of the body sections. According to the present invention, however, the 10 connection of one of the body sections to the corresponding tube is broken on extending the pencil to uncover the lead supply groove. The broken connection leaves one of the tubes free, and reverse action may then be effected by mere pressure on the forward end of the exposed pin by 15 the new lead.

Further, the feeding mechanism is so constructed that initial pressure on the expelling pin moves the pin into the pencil body and then 20 relatively inward of the carrier member, whereby the latter may engage the lead. After the lead has thus been engaged in the carrier, both the pin and the carrier move at the same rate inward of the pencil body. The new lead is inserted as far 25 as desired, and the pencil body is then contracted to cover the lead delivery slot and to re-establish the driving connection which was previously broken.

The invention is fully described by way of an 30 example in the following description and in the accompanying drawing in which:

Figure 1 is an elevation of the device;

Figure 2 is a longitudinal section;

Figure 3 is an elevation of the device, partly in 35 section, in pulled out condition for delivery of a new lead;

Figures 4 and 5 are sections on the lines 4—4 and 5—5 respectively of Figures 2 and 3;

Figure 6 is a section on the line 6—6 on Figure 40 2, and

Figure 7 is a detail elevation of the forward end of the spiral.

Reference to these views will now be made by use of like characters which are employed to designate corresponding parts throughout.

The device may be regarded as assembled on and in an operating tube 1 on which are mounted three casing sections namely, an upper section 2, an intermediate section 3 and a lower section 4, 50 the latter having a tapering lower end 5. The upper section 2 is slideable on the tube 1 so that it may be removed to expose the eraser 7 held in the upper end of the tube 1. The section 2 may have a liner 6 if desired. Also, on removal of 55

the eraser, leads 8 may be dropped into the operating tube which functions as a magazine, as will presently be described.

The intermediate section 3 is fixed firmly on the tube 1 so that the latter may be pulled outwardly with respect to the lower section 4 as will presently appear. To facilitate such relative sliding movement, the section 4 is spaced from the operating tube at 9, but the parts are nevertheless maintained in rotatable relation by means of a bushing or bearing 10 inserted between them at the upper end of the section.

The feed mechanism is for the most part conventional, consisting of a spiral tube 11 and a channel tube 12 mounted one within the other in the axis of the pencil. In this case the channel tube is within the spiral and projects into the tapered end 5 where it receives a tip 13 screwed thereon at 14 whereby the channel tube is held in fixed position. A spacer 15 is inserted in the end 5 behind the tip 13, and the spiral tube rests thereon as may be seen in Figure 2. The lower end of the spiral tube is surrounded by a clutch member 16 securely fixed thereon and consisting of a serrated or corrugated ring as may be seen more clearly in Figures 3 and 7. The lower end of the operating tube is reduced in diameter and also serrated or corrugated, as indicated by the numeral 17, to serve as a complementary clutch member, and is adapted to slide on and off the member 16. Thus, on pulling the operating tube outwardly by means of the intermediate section 3, the driving connection between the operating tube and the spiral tube is broken, as illustrated in Figure 3.

The channel tube slidably receives a lead carrier in the form of a split tube 18 adapted to hold a lead 19 in its lower end by friction, such lead passing through the tip 13 in the usual manner. The carrier tube 18 is formed with a finger 20 extending into the groove 21 of the spiral tube after passing through the slot 12' of the channel tube 12. The carrier tube, in turn, receives a slidably expelling pin 22 bearing against the rear end of the lead 19 and having its rear end formed as a finger 23 to pass through the slot 12' and into the groove of the spiral at a point behind the finger 20.

The upper end of the channel tube is flanged outward at 24, and beneath the flange a washer 25 is fixed on the channel tube. This washer is of such size as to be engaged by the reduced portion 17 of the operating tube 1 when the latter is drawn outwardly as illustrated in Figure 3. Between the washer 25 and the upper end of the spiral tube is mounted a free or rotatable washer 26 for a purpose which will presently appear.

The lower part of the operating tube is formed with a lengthwise groove 27 of slightly less length than a standard lead. When the parts are in the working position shown in Figure 2, the upper end of this groove is disposed at or slightly below the lower end of the intermediate section 3. Finally a block 28 with an inclined upper face 29 is held by a press fit in the operating tube at the upper end of the groove 27. The groove aids in securing the block in the tube, and it will be seen in Figure 2 that the upper face of the block constitutes the bottom of the lead magazine 30 provided in the upper part of the operating tube beneath the eraser 7.

In the use of the device as thus far described, one of the leads 8 will gravitate into the groove 27 during the ordinary manipulation of the pencil. In order to make this lead accessible for re-fill pur-

poses, the operating tube 1 is pulled outwardly by a pull on the section 3 so that the parts assume the position shown in Figure 3 wherein the groove 27 and lead therein are exposed, except for the upper extremity 31 thereof to prevent the lead from falling out. The lead may be gripped at finger dents 32 formed at opposite sides of the groove 27, as shown in Figures 3 and 5. As a result of this outward movement of the operating tube 1, the clutch 16, 17 is released as shown in Figure 3, 10 and the outward movement of the operating tube 1 is limited by the engagement of the reduced portion 17 with the washer 25, the latter in turn being stopped against the flange 24 of the anchored channel tube 12. The intermediate section 3 carries an indicator 33 placed in line with the groove 27, so that the user may have the groove uppermost when pulling the operating tube outward.

The spiral groove 21 terminates at its forward end in a circumferential portion forming a shoulder 34 disposed at zero pitch transversely of the axis of the pencil. This portion terminates in a stop or shoulder 35. Directly behind the shoulder 34, the width of the spiral groove is increased as indicated by the numeral 36 in Figures 3 and 7. The widening is accomplished by cutting away the upper edge of the groove through an extent of about 180° around the spiral tube, from the shoulder 34, as indicated by the numeral 37, thereby also reducing the pitch of the spiral where cut.

The normal distance between convolutions of the spiral groove 21 is such that the forward end of the expelling pin 22 is within the carrier tube 12 so that the rear end of the lead 19 may be received in the carrier in the usual manner as shown in Figure 2. This relation is maintained as the lead 19 is fed out until the pin 20 reaches the shoulder 34. From this point on, the carrier tube 40 does not go forward, but the expelling pin continues its forward movement so that its forward end passes beyond the forward end of the carrier tube, thereby expelling the remaining fragment of lead in the usual manner. At this time, the forward end of the expelling pin 22 may usually be seen protruding beyond the end of the tip 13, as shown in Figure 3.

In order to refill or reload the carrier tube, the operating tube is pulled out as described in connection with Figure 3, thereby exposing a lead in the groove 27 and also disengaging the clutch 16, 17, whereby the spiral tube 11 is no longer held against rotation. The lead taken from the groove 27 is pushed against the exposed end of pin 22 whereupon the latter moves rearward and the free spiral tube rotates inasmuch as the pin 23 is in the spiral part of the groove 21, and the channel tube 12 is anchored. The loose washer 26 facilitates rotation of the spiral tube in case this washer is pushed into engagement with the larger washer 25. There is no similar backward movement of the carrier tube as long as its finger 20 rides along the square shoulder 34. The length of the shoulder 34 is such as to permit the forward end of the pin 22 to come flush with the forward end of the carrier tube by the time the pin passes from the shoulder 34 into the widened groove 36 at the reduced pitch shoulder 37. This shoulder permits the carrier tube to begin moving rearward and at the same time causes further relative movement between the expelling pin and the carrier tube until both fingers 20 and 23 have entered the uniformly spaced parts of the spiral groove 21. By this time, as a result of this

relative movement the carrier tube 18 has been pushed over the forward end of the expelling pin 22 and over the rear end of the newly inserted lead. This action is inherent in the spacing of the convolutions of groove 21 with relation to the expelling pin and carrier tube.

The widening of the spiral groove at 36 plays no part in the loading operation, but the difference in pitch causes the overlapping of the carrier tube 18 on pin 22 as already set forth. The reverse of this overlapping action is not desired, however, on the feeding movement before carrier finger 20 has reached spacer 15. The widened groove is therefore provided in order to permit, on the feeding movement, a free movement of finger 20 so that tube 18 and pin 22 travel at the same speed by propulsion at finger 23 and the frictional connection between the lead and the carrier tube, with no expelling of the lead until finger 20 bears on spacer 15. It will thus be seen that while on the loading operation finger 20 is guided by the reduced pitch shoulder 37, it is guided on the feeding operation by spacer 15.

It may now be seen that a new lead is readily delivered from the magazine without disassembling any part of the pencil structure and without danger of spilling the leads remaining in the magazine. It is also to be noted that the pulling of the upper section 2 outwardly to expose the lead delivery groove also conditions the feeding mechanism for the free reverse action by the pressure of the lead inwardly on the forward end of the expelling pin 22. Finally, the return of the section 2 to its normal position causes the operating tube 1 to be connected again to the spiral tube 11 at the clutch 16, 17. The operating tube, in turn, may be rotated, in the normal operation of the device, by turning either section 2 or 3, there being sufficient friction between the operating tube and the section 2 to enable actuation by turning the member 2.

Although a specific embodiment of the invention has been illustrated and described, it will be understood that various alterations in the details of construction may be made without departing from the scope of the invention, as indicated by the appended claims.

What I claim is:

1. A pencil having two relatively rotatable and axially shiftable body sections and feeding mechanism including two relatively rotatable parts one within the other and attached respectively to said body sections and operable by rotation of one of the body sections, and a slideable feed member within said parts and propelled thereby on relative rotation of said body sections in one direction, one of said body sections being readily detachable from the corresponding mechanism part on relative axial shifting of one of said body sections, whereby said mechanism parts become freely movable relatively to each other in the reverse direction by axial inward pressure on said feed member.

2. A pencil comprising upper and lower casing sections rotatably and slidably mounted relatively to the other, a lead chamber formed within the upper section and having a delivery groove rendered accessible on sliding said sections apart, feeding mechanism including two relatively rotatable parts one within the other and attached respectively to said body sections and operable by rotation of one of the body sections, and a slideable feed member within said parts and pro-

pelled thereby on relative rotation of said body sections in one direction, one of said body sections being readily detachable from the corresponding mechanism part on relative axial shifting of one of said body sections, whereby said mechanism parts become freely movable relatively to each other in the reverse direction by axial inward pressure on said feed member.

3. A pencil comprising an operating tube, upper and lower casing sections mounted thereon, the upper section being rotatable and slideable relatively to the lower section, feeding mechanism comprising two relatively rotatable parts, one within the other and attached respectively to said operating tube and lower casing section, and a slideable feed member within said parts and propelled thereby on relative rotation of said casing sections in one direction, the operating tube being detachable from the corresponding mechanism part on sliding said casing sections apart, whereby said mechanism parts become freely movable relatively to each other in the reverse direction by axial inward pressure on said feed member.

4. A pencil comprising an operating tube, upper and lower casing sections mounted thereon, the upper section being rotatable and slideable relatively to the lower section, feeding mechanism comprising two relatively rotatable parts, one within the other and attached respectively to said operating tube and lower casing section, a slideable feed member within said parts and propelled thereby on relative rotation of said casing sections in one direction, the operating tube being detachable from the corresponding mechanism part on sliding said casing sections apart, whereby said mechanism parts become freely movable relatively to each other in the reverse direction by axial inward pressure on said feed member, the upper portion of said operating tube being adapted as a magazine for leads, and lead-delivery means below said magazine portion and exposed on sliding said sections apart.

5. A pencil comprising an operating tube, upper and lower casing sections mounted thereon, the upper section being rotatable and slideable relatively to the lower section, feeding mechanism comprising two relatively rotatable parts, one within the other and attached respectively to said operating tube and lower casing section, a slideable feed member within said parts and propelled thereby on relative rotation of said casing sections in one direction, the operating tube being detachable from the corresponding mechanism part on sliding said casing sections apart, whereby said mechanism parts become freely movable relatively to each other in the reverse direction by axial inward pressure on said feed member, the upper portion of said operating tube being adapted as a magazine for leads, said tube being formed with a lead-receiving groove below said magazine and in communication therewith, said groove being exposed on sliding said sections apart.

6. A pencil comprising an operating tube, upper and lower casing sections mounted thereon, the upper section being rotatable and slideable relatively to the lower section, feeding mechanism comprising two relatively rotatable parts, one within the other and attached respectively to said operating tube and lower casing section, a slideable feed member within said parts and propelled thereby on relative rotation of said casing sections in one direction, the operating tube being detachable from the corresponding mechanism part on sliding said casing sections apart, whereby said mechanism parts become freely movable rela-

- tively to each other in the reverse direction by axial inward pressure on said feed member, the upper portion of said operating tube being adapted as a magazine for leads, said tube being formed with a lead-receiving groove below said magazine and in communication therewith, said groove being exposed on sliding said sections apart, and an inclined bottom piece in said magazine and sloping downwardly toward said groove.
10. 7. A pencil comprising an operating tube, upper and lower casing sections on said tube, the lower section being rotatable and slideable on said tube, the upper section being movable with said tube and relatively to the lower section, feeding mechanism in said tube including two relatively rotatable parts one within the other and attached respectively to said lower section and tube, and a slideable feed member within said parts and propelled thereby on relative rotation of said sections in one direction, the operating tube being detachable from the corresponding mechanism part on sliding of said sections apart, whereby said mechanism parts become freely movable relatively to each other in the reverse direction by axial inward pressure on said feed member.
8. A pencil comprising an operating tube, upper and lower casing sections on said tube, the lower section being rotatable and slideable on said tube, the upper section being movable with said tube and relatively to the lower section, feeding mechanism in said tube including two relatively rotatable parts one within the other and attached respectively to said lower section and tube, a slideable feed member within said parts and propelled thereby on relative rotation of said casing sections in one direction, the operating tube being detachable from the corresponding mechanism part on sliding of said sections apart, whereby said mechanism parts become freely movable relatively to each other in the reverse direction by axial inward pressure on said feed member, the upper portion of said operating tube being adapted as a magazine for leads, and lead-delivery means below said magazine portion and exposed on sliding said sections apart.
9. A pencil comprising an operating tube, upper and lower casing sections mounted thereon, the upper section being rotatable and slideable relatively to the lower section, the feeding mechanism including a spirally grooved tube and a channel tube one within the other and attached respectively to said operating tube and lower casing section, the operating tube being detachable from the corresponding mechanism tube on pulling said sections apart, a slideable carrier member within said tubes and having a finger passing laterally through said tubes, and a slideable expelling pin in said carrier member, adapted to pass forwardly therethrough and having a finger extending laterally through said tubes, the forward portion of the spiral groove having a reduced pitch angle adapted to receive the finger of said carrier member to reduce the axial speed of said carrier member relatively to said pin.
10. 10. A pencil comprising an operating tube, upper and lower casing sections mounted thereon, the upper section being rotatable and slideable relatively to the lower section, and feeding mechanism including a spirally grooved tube and a channel tube one within the other and attached respectively to said operating tube and lower casing section, the operating tube being detachable from the corresponding mechanism tube on pulling said sections apart, a slideable carrier member within said tubes and having a finger passing laterally through said tubes, and a slideable expelling pin in said carrier member, adapted to pass forwardly therethrough and having a finger extending laterally through said tubes, the forward portion of the spiral groove having a reduced pitch angle adapted to receive the finger of said carrier member to reduce the axial speed of said carrier member relatively to said pin.
11. A pencil comprising an operating tube, upper and lower casing sections mounted thereon, the upper section being slideable relatively to the lower section, the upper portion of said operating tube being adapted to contain leads, and lead-delivery means formed in said operating tube below and in communication with said portion and exposed on sliding said sections apart.
12. A pencil comprising an operating tube, upper and lower casing sections mounted thereon, the upper section being slideable relatively to the lower section, the upper portion of said operating tube being adapted to contain leads, said tube being formed with a lead-receiving groove below said portion and in communication therewith, said groove being exposed on sliding said sections apart.
13. In a pencil of the class described, a tubular member having a groove, mechanism engageable with a lead including a follower member extending within said groove and movable lengthwise within said tubular member, plunger means connected with said follower member being movable within the tubular member in response to the engagement therewith of one end of an inserted lead, without necessitating the disengagement of the follower member from the groove, and a second tubular member having a groove for receiving said follower member, and cooperating with the other tubular member to guide the follower member.
14. In a pencil of the class described, a tubular member having a spiral groove, a follower means for longitudinally actuating a lead and having a portion for engagement with a lead, said follower means including a follower member extending within the spiral groove and plunger means connected therewith and adapted to be moved lengthwise within the pencil in response to relative rotative movement between the follower member and the tubular member, said follower means being movable inwardly within the casing in response to the engagement therewith by an inserted lead without disengaging said follower member from the spiral groove, and a second tubular member having a longitudinal groove for receiving said follower member and cooperating with the other tubular member to produce said relative rotative movement.
15. In a pencil of the class described, a pair of relatively rotatable tubular members, one of said members within the other, one of said members being provided with a spiral groove, and the other a longitudinal groove, a follower member for longitudinally shifting a lead, said follower member extending into the grooves and adapted in response to relative rotation between said tubular members to be reciprocated longitudinally thereof, and shiftable means operable in one position for securing one of said tubular members in fixed position with respect to the tip of the pencil structure, and when in another shifted position for releasing said tubular member.
16. In a pencil of the class described, a pair of

5 relatively movable tubular members, one of said members within the other, one of said members being provided with a spiral groove, and the other a longitudinal groove, a follower member for longitudinally shifting a lead, said follower member extending into the grooves and adapted to be longitudinally reciprocated in response to relative movement between said tubular member, and shiftable means operable in one position for securing one of said tubular members in a fixed position with respect to the tip of the pencil structure.

10 17. In a pencil of the class described, a pair of relatively rotatable tubular members, one of said members within the other, one of said members being provided with a spiral groove, and the other a longitudinal groove, a lead actuating follower member extending within said grooves and adapted to be reciprocated longitudinally of the tubular members in response to relative movement thereof, and shiftable means operable when in one position for securing one of said tubular members in a fixed position against rotation with respect to the tip of the pencil structure, and 25 when in another shifted position for releasing said tubular member, said locking and releasing means being operable at any stage of the operation of the follower member.

18. In a pencil of the class described, a pair of tubular members, one of said members being rotatable within the other member and provided with a spiral groove, the other member having a longitudinal groove provided therein, a lead actuating follower member extending within said grooves and adapted, when a lead is inserted through the tip of the pencil, to cause rotation of the spirally grooved tubular member and thereby effect displacement of said follower member longitudinally of said tubular members to an alternate position within the pencil, and locking means for securing said spirally grooved tubular member against rotation with respect to the tip of the pencil structure, whereby to permit of forward longitudinal movement of the lead actuating member.

19. In a pencil of the class described, a pair of relatively rotatable tubular members, one of said members being inside of the other, a cap, one of said tubular members being connected at one end 50 of the pencil with said cap, the other member being adapted to be secured at the opposite end of the pencil, one of said members being provided with a spiral groove, and the other a longitudinal groove, a lead actuating follower member within one of said tubular members having a section extending into said spiral groove, and means for locking one of said tubular members against rotation with respect to the top of the pencil structure to thereby effect the forward movement of the lead actuating follower member in response to rotation of the other member and for releasing said first mentioned tubular member, whereby said follower member may be pushed back within the pencil by engaging the same with the 60 end of an inserted lead to thereby effect the refilling of the pencil.

20. A pencil of the class described, a pair of relatively rotatable tubular members, one member being within the other, a cap connected with one of said members for effecting rotation thereof, one of said members being provided with a spiral groove and the other with a longitudinal groove, a lead actuating follower member positioned within said tubular members and projecting within said grooves, whereby said member

may be reciprocated within the tubular members in response to relative rotation of said members, the forward movement of the follower member being occasioned in response to rotation of the cap, and means for securing one of the tubular members against rotation with respect to the tip of the pencil structure whereby relative rotation between the tubular members may be effected in response to the rotation of said cap, said means being releasable to render the follower member capable of being pushed back within the pencil without rotation of said cap.

21. In a pencil of the class described, a pair of tubular members, one of said members being provided with a spiral groove and the other with a longitudinal groove, a cap fixed to one of said tubular members for imparting rotation thereto, a lead carrier associated with said spiral and longitudinal grooves and positioned within one of said tubular members, whereby relative rotation between said tubular members will cause longitudinal movement of the carrier, and means positioned at one end of the pencil for securing one of the tubular members against rotation with respect to the tip of the pencil structure whereby forward movement of the lead carrier may be obtained in response to rotation of the cap, said means being adapted to be released so that the lead carrier may be readily pushed back to a shifted position.

22. In a pencil of the class described, a tubular member having a longitudinal slot, a cap secured to said tubular member, a second tubular member having a spiral groove, a lead actuating follower member extending within said longitudinal and spiral grooves and positioned within one of said tubular members, and means for securing said spirally grooved tubular member against rotation, with respect to the tip of the pencil structure while the lead actuating member is being moved in one direction, said means being releasable, whereby the follower member may be retracted for the purpose of refilling.

23. In a pencil of the class described, a tubular member having a longitudinal groove, a cap secured to said tubular member, a second tubular member having a spiral groove, a lead actuating follower member extending within said spiral and longitudinal grooves and positioned within one of said tubular members and adapted, in response to relative rotation between said tubular members, to be longitudinally reciprocated, the forward movement of the follower member being occasioned in response to rotation imparted to the cap, and shiftable means operable when in one position for securing the spirally grooved tubular member against rotation with respect to the tip of the pencil structure, said means being operable when in another shifted position for releasing said tubular member.

24. In a pencil of the class described, a pair of relatively rotatable tubular members, one of said members being positioned inside of the other, each of said members being provided with a groove, a follower member for engaging a lead, a portion of said follower member extending within the grooves of said tubular members and adapted, in response to relative rotation between said tubular members to be reciprocated longitudinally thereof, a cap operatively connected to one of said members, and means for securing or releasing one of the tubular members with respect to the tip of the pencil structure so as to enable free rotation of said member relative to

the other tubular member when the follower member is pushed back within the pencil.

25. A pencil having two relatively rotatable and axially shiftable casing sections and feeding mechanism including a spirally grooved tube and a channel tube one within the other and attached respectively to said casing sections and operable by rotation of one of said sections, a slidable carrier member within said tubes and having a finger passing laterally through the grooves in said

tubes, and a slidable expelling pin in said carrier member, adapted to pass forwardly therethrough and having a finger extending laterally through said grooves, the forward portion of the spiral groove being widened to permit a free movement of the carrier finger and carrier to their extreme forward position before said pin begins to pass forwardly through said carrier member. 5
